SHELL MAKING PROCESS

George R. Eckstein, Bridgeport, Conn., assignor
to Remington Arms Company, Inc., Bridgeport,
Conn., a corporation of Delaware

Application July 13, 1945, Serial No. 604,777

4 Claims. (Cl. 29—1.3)

1

This invention relates, in general, to the manufacture of ammunition, and, more especially, to an improved method of manufacturing all metal shot shells, and, although the following description refers particularly to the production of an aluminum shot shell, it will be understood that the method has other applications and may be successfully used for producing small arms ammunition components and similar seamless metal tubular articles.

Some efforts have been made heretofore to extrude cartridge cases, but these efforts have not culminated in success due primarily to the persistent separation of body and head on firing. This phenomenon occurs most frequently in shot shells of small diameter (.410) because of the extraction difficulties which they offer and the fact that they have the highest pressure level of any shot shell.

The occurrence of head and body separation is believed to result from a small but appreciable set-back of the bolt in substantially all bolt action commercial guns at the time of firing. One explanation for head separation is that, since the thickness of the wall of a cartridge case or shot shell, and, in particular its powder chamber portion, changes from head to mouth by only a relatively small amount, the entire wall expands substantially simultaneously into gripping engagement with the wall of the barrel chamber. This is sometimes referred to as obturation. The obturation of this relatively large area of the wall of the case effectively holds the entire case from moving rearwardly and the pressure acting on the relatively unsupported head (due to bolt setback) will force the head rearwardly causing a transverse rupture to occur between the head and the body of the case. A second theoretical explanation is that the obturation of the relatively large area of the wall of the case prevents a uniform overall longitudinal expansion of the case (which, if permitted, might conceivably take up bolt setback) and again encourages a local stretching of the case such as to cause a transverse rupture.

The present invention has its inception in that the discovery that the separation of the body and head may be effectively prevented by forming walls of a prescribed geometry such that a proper obturation pattern is obtained. Specifically, it has been found that a case having walls which increase in thickness from the mouth of the case to the base of the head will not be subject to head separation. A possible explanation is that because of the variable wall section, a local obturation is effected which is insufficient either

2

to prevent the case from elongating as a whole so as to take up bolt set-back or to hold the case firmly in the chamber so as to enable movement of the head relative to the body of the case.

5 All previously known methods of forming drawn and/or extruded small gauge shot shells have been found inadequate and impractical economically for producing cases having the wall geometry necessary to prevent head separations.

10 It is a general object of this invention to provide a method of producing all metal shot shells which will not develop head separations on firing. It is a further object of this invention to provide an improved method of producing an aluminum

15 shot shell by extruding a seamless metal tubular case having walls of varying cross section, and then forming a head at one end of the case. A particular object of this invention is the provision of an improved method of producing an aluminum shot shell by first extruding a seamless metal tube, the walls of which increase in thickness from the base of the tube to its open upper end, inverting a relatively thick wall section at the upper end of the tube to provide material for forming a head, and then heading the tube to form a finished shell.

20 These and other objects, features and advantages of the invention will be more fully understood upon reference to the following description taken in conjunction with the accompanying drawings, in which:

Fig. 1 is a vertical cross sectional view showing a punch and die assembly adapted to express a slug positioned in the die.

25 Fig. 2 is a cross sectional view similar to Fig. 1, the parts being in the positions occupied at the end of the extruding operation.

Fig. 3 is a longitudinal sectional view of the extruded tube.

30 Fig. 4 is a cross sectional view similar to Fig. 3, but showing the closed end of the tube cut off.

Figs. 5 through 8 are cross sectional views of a die and a punch set used in successive order to invert a portion of the profile of the tube.

35 Fig. 9 is a longitudinal sectional view of the tube having an inverted profile.

Fig. 10 is a longitudinal sectional view of the completed shot shell.

40 Referring to the drawings, the extruding apparatus comprises a die 15 having a die aperture indicated generally at 16 and comprising a conical bottom 17 preferably roughened as shown to insure optimum performance, slightly tapered side walls 18 and rounded shoulders 19 which join the tapered side walls 18 to the base

of a substantially cylindrical counterbore 20 in the upper end of the die aperture. The specific geometry of the die aperture is particularly suited for extruding the .410 shot shell. It will be understood, however, that modifications thereof are included within the scope of this invention for extruding shells of other sizes.

The aluminum slug 22 from which the extruded tube is formed is preferably stamped or coined to have a shape conforming substantially to the profile of the die aperture, all edges of the slug being smooth and rounded. A conical recess 24 is shown in the top of the slug to facilitate longitudinal alignment of the axes of the punch and slug. The recess 24 may also be used as a pocket 15 for holding a lubricant.

The punch 25 is provided with a conical nose 25', the base of which comprises a narrow substantially cylindrical land 26 of slightly greater diameter than that of the shank portion of the punch and joined thereto by a skirt 27 having outwardly tapering walls, the angle of the taper being substantially 3° in the embodiment shown. The punch and die assembly are suitably mounted in a press of the type well known in the art and which need not be illustrated or described here since it forms no part of the invention.

As the punch 25 moves down into the die 15, the metal of the slug is moved both radially and upwardly into the space between the punch land 26 and the wall 20 of the counterbore, this movement of the metal being hereinafter referred to as reverse extrusion. Initially, the width of the space between the land and counterbore 20 of the die remains substantially constant and the extruded flange 30 formed therebetween comprises a relatively thick wall section having a substantially cylindrical profile 32, as shown in Figs. 2 and 3. However, as the land approaches the rounded shoulder 19 of the die, the flow of metal is restricted so that the cross section of the wall of the extruded tube is decreased forming the tapered portion 33 at the base of the flange 30. The small radius of the shoulder 19 produces a relatively abrupt reduction in thickness of the extruded metal and thereafter as the land 26 moves down below the shoulder 19 of the die, the cross section of the wall of the tube being extruded decreases in thickness more slowly corresponding substantially to the taper of the wall 18 of the die aperture. The completely extruded tube is shown at 28 in Fig. 3. The bottom of the tube is closed by an integral conical cap 34. It will be noted that the inside diameter of the tube is substantially constant throughout its length, and that the outside diameter increases steadily from the closed end of the tube to its open upper end. This external taper matches exactly the taper of the .410 shot shell chamber and constitutes the external taper of the finished shell.

The next step in forming the shell is to cut off the conical cap 34. This operation and the subsequent process of inverting the profile of the enlarged wall section or flange 30 are done at successive stations of a horizontal dial press of a well known type. The cap cut off is preferably accomplished by a rapidly rotating saw mounted on the press.

Following cut off, the tapered tube 35, see Fig. 4, is forced through a die by a plurality of punches of different sizes, as illustrated in Figs. 5, 6, 7 and 8 so as to transfer the profile of the external flange 30 onto the inside of the tube, this process being termed profile inversion. To this end, the tube is inserted with its small end

first into a die 36, the aperture of which comprises a bore 37 having a taper corresponding substantially to the taper of the outer wall of the tube; and a countersink 37' constituting a relatively steep tapered surface. Initially, a punch 38 having a frusto-conical nose 39, the base diameter of which corresponds substantially to the major diameter of the countersink 37' is adapted to force the flange portion 30 of the tube into the countersink 37' thereby moving the metal of the flange inwardly radially to the extent shown in Fig. 5.

Following this, the punch 38 is withdrawn from the die 36 and a second punch 40 is entered into the die to push the tube further into the bore 37. The profile of the nose of the punch 40 is substantially identical to that of the punch 38, but is of smaller base diameter. This second step brings more metal of the flange 30 to the inside of the case, as shown in Fig. 6. The final working step is shown in Figs. 7 and 8, in which a third punch 42 of still smaller diameter but having a similar nose profile completes the process of pushing the tube 35 through the die, the result of which is to force all of the metal of the flange 30 to the inside of the tube. The profile of the resulting restriction 43 in the tube comprises a substantially cylindrical section 44 and a relatively abrupt taper 45, and, in these respects, is substantially the reverse of the original profile of the flange or heavy external wall section of the tube. The outside profile of this section of the tube has been made substantially cylindrical as indicated at 46 in Fig. 9.

The particular profile inversion die and punch assemblies shown in Figs. 4 through 7 are for forming the .410 aluminum shot shell and to this end the punches 38, 40 and 42 are substantially 0.625 inch, 0.525 inch and 0.450 inch in diameter respectively. Moreover, for optimum performance, the angle of the frusto-conical nose of each punch is substantially 33° which is considered critical for the extrusion of aluminum.

Following profile inversion, the tube is transferred to a conventional case heading machine which embodies a heading die the bore of which has a taper equal to the external taper of the tube, the die being fixedly supported in axial alignment with and between the workpiece engaging ends of a horizontally mounted reciprocable punch and bunter. The tube is inserted into the heading die with the inverted profile end of the tube opposite the bunter. The punch is then moved into the opposite end of the tube until the end of the punch engages the restriction 43 formed therein by the metal of the inverted profile and thereafter the heading bunter is moved forcefully into engagement with the adjacent open end of the tube causing the metal which constitutes the inverted profile to flow inwardly substantially radially around the primer pocket-forming nib of the bunter and to form a solid head having a primer pocket 47, flash hole 48 and an extraction rim 49. It will be noted that the metal is relatively free to flow inwardly radially because of the central aperture of the inverted profile and hence the heading operation is characterized by relatively low pressure and optimum flow patterns which preclude the formation of cold shuts and similar heading defects. Simultaneously with the formation of the head, the substantially cylindrical portion 46 of the case is tapered to blend into the original external taper of the walls and an appreciable taper 50 which increases in width from its junction with

the substantially cylindrical internal walls of the case to the base of the head is formed on the inside of the case.

The case or shell formed by the above described process has, therefore, walls which increase in thickness from the mouth of the shell to its base. Moreover, the taper is relatively complex. For the .410 aluminum shot shell this taper is exemplified by a wall thickness of substantially 0.035 inch at the junction of the base of the shell and its wall, a wall thickness of substantially 0.019 inch within one-half an inch of the base formed by the tapered exterior wall and the tapered interior wall of the case and thereafter a gradual external taper to a wall thickness of substantially 0.010 inch at the mouth of the shell. It should be emphasized that the final external taper of the major portion of the shell is formed during the extrusion operation and that during the heading operation a similar taper is impressed on the headed section of the shell so that a fully tapered shell is formed without a conventional tapering operation.

This specific taper provides an optimum obturation pattern for the .410 shot shell such that head separation is virtually eliminated, and, although the process has been described with relation to the use of aluminum, it will be understood that other metals and alloys of aluminum may be used.

What is claimed is:

1. A method of producing a cartridge case having walls of a predetermined geometry such as to preclude head separations on firing comprising the steps of extruding a thin walled tube having a heavy externally flanged wall section at one end, then completely inverting the profile of said externally flanged wall section by radially swaging same to provide a heavy flange on the inside of said tube, partially closing said one end and then heading said tube by deforming said heavy flanged section.

2. A method of producing a cartridge case having walls of a predetermined geometry such as to preclude head separations on firing comprising the steps of extruding a tube having tapered walls and a heavy externally flanged wall section at the upper end of said tube, then completely inverting the profile of said heavy externally flanged wall section by radially swaging same to provide a heavy flange on the inside of

said tube partially closing said upper end, and then heading said tube by deforming said heavy flanged section.

3. A method of producing in successive operations a metal shot shell comprising the steps of extruding a tube having a relatively thin wall of constant internal diameter and an external taper corresponding to the final taper of a finished shell and a heavy externally flanged wall section at the upper end of said relatively thin wall, completely inverting the profile of said flanged wall section by radially swaging same to transfer said heavy wall section to the inside of said tube and partially close said upper end then radially supporting said tube and axially contracting said inverted profile heavy wall section to impress an external taper on said tube adjacent said heavy wall section corresponding to and blending with the external taper of said relatively thin wall.

4. A method of producing in successive operations a metal shot shell comprising the steps of extruding a tube having a relatively thin wall of constant internal diameter and an external taper corresponding to the final taper of a finished shell and a heavy externally flanged wall section at the upper end of said relatively thin wall, completely inverting the profile of said flanged wall section by radially swaging same to transfer said heavy wall section to the inside of said tube and partially close said upper end, then radially supporting said tube both externally and internally at predetermined contour limits and axially contracting said heavy wall section simultaneously to impress an external taper on said tube adjacent said heavy wall section corresponding to and blending with the external taper of said relatively thin wall and to form a solid head on said tube having a primer pocket, a flash hole and an extracting rim.

GEORGE R. ECKSTEIN.
